CLOTH-CUTTING MACHINE

Samuel Segal, Brooklyn, N. Y.

Application June 18, 1936, Serial No. 85,918

9 Claims. (Cl. 51—249)

The present invention is a new and useful cloth cutting machine wherein a movable blade is sharpened by a pair of grinding wheels adapted to be oscillated for alternately impacting opposing faces of the blade to produce a relatively sharp and durable cutting edge. More particularly, however, the invention is concerned with a cloth cutting machine having a reciprocable blade and reciprocable and oscillatable means for sharpening the blade during its reciprocation within the holder or guard thereof.

It is an object of the invention, among others, to provide in a cloth cutting machine, sharpening means adapted to be swung forwardly of the cutting edge of the blade for alternately impacting during oscillation thereof opposing faces of the blade to form the desired cutting edge during reciprocation of the blade, and adapted to be conveniently and readily shifted or swung to the rear of the blade and away from its cutting edge pursuant to sharpening operations.

It is another object of the invention to provide an improved blade having a plurality of spaced teeth integrally interconnected by spaced reduced portions having relatively less resistance to wear during sharpening by the grinding wheels than the body of the blade.

It is a further object to provide a cloth cutting machine wherein a movably guided blade includes a plurality of teeth defining an irregular or toothed cutting edge and forming a plurality of spaced grooves in alignment with relatively reduced portions of the blade whereby during sharpening operations the grinding wheels straddling the blade cooperate with the irregular contour of cutting edge to maintain said contour.

It is a further object of the invention to provide in an improved cloth cutting machine means for adjusting and indexing the grinding wheels in respect to the cutting edge thereof preparatory to sharpening operations.

It is another object to provide a cloth cutting machine sharpening holding or supporting means conveniently adapted to be bodily removed from the cutting machine or readily applied thereto bodily.

Other objects, advantages and features of the invention are in part obvious and in part hereinafter more particularly set forth.

The present invention will be best understood from the following discussion of the several typical structural embodiments, reference being had to the accompanying drawings in which:

Fig. 1 is a side elevational view of the cloth cutting machine according to the invention,

shown partly in section and further illustrating in full lines the sharpening wheels disposed forwardly of the blade with the supporting carriage thereof in an unlocked position and having its rotatable shaft unlocked and adapted to be swung rearwardly of the blade in a clockwise direction as shown by the dash lines to arrange the sharpening wheels in back of the blade as indicated by the dash and dot lines.

Fig. 2 is a side view of my improved blade 10 shown on a larger scale.

Fig. 3 is a sectional view on the line 3—3 of Fig. 2.

Fig. 4 is a sectional view on the line 4—4 of Fig. 2.

Fig. 5 is a front view of Fig. 1, shown partly broken away.

Fig. 6 is a sectional view on the line 6—6 of Fig. 1.

Fig. 7 is a fragmentary view of Fig. 1 illustrating the slidable carriage supporting the sharpening means unlocked and adapted to be reciprocated relative to the reciprocable blade.

Fig. 8 is a fragmentary view of Fig. 1 showing the slidable carriage in a locked position and the grinding wheels disposed at the rear of the blade.

Fig. 9 is a sectional view taken on the line 9—9 of Fig. 7, illustrating several positions of the oscillatable carriage and its grinding wheels in full and in dash and dot lines.

Fig. 10 is a sectional view on the line 10—10 of Fig. 9.

Fig. 11 is a fragmentary view illustrating a sharpening holding unit adapted to be bodily applied to or removed from the machine.

Fig. 12 is a sectional view on the line 12—12 of Fig. 11.

Fig. 13 is a fragmentary view of a cloth cutting machine according to the invention illustrating a modified means for oscillating a sharpening supporting carriage of the type disclosed in connection with the form shown in Figs. 1—10 inclusive.

Fig. 14 is a sectional view on the line 14—14 of Fig. 13.

Fig. 15 is a fragmentary side view of a cloth cutting machine showing a modified sharpening holding unit bodily removable from the guard and base of the machine.

Fig. 16 is a sectional view on the line 16—16 of Fig. 15.

Fig. 17 shows a blade according to the invention for use in connection with a cloth cutting machine adapted to use a circular blade and

Fig. 18 is a sectional view along the line 18-18 of Fig. 17.

The cloth cutting machine is generally designated 10 and comprises the usual base 11, up-standing knife guard 12 from which the rearwardly disposed platform of arm 13 extends and on which depending lug 14 of the electric motor or prime mover casing 15 is appropriately secured. Shaft 16 of the motor rotates the relatively heavy crank 17 eccentrically actuating connecting rod 18 which in turn has its closed and looped end loosely associated with wrist pin 19 of the cross head 20 vertically and slidably guided in a raceway formed by the spaced tracks 21 and 22. By the present arrangement rotary motion of shaft 16 is translated into reciprocating motion.

Cross head 20 carries a clamping plate 24 (see Fig. 6) which may be controlled by a nut 25 threaded on bolt 26. The upper bifurcated portion 27 of blade 28 straddles the shank of bolt 26 and is secured against the crosshead by the clamping plate 24 under the influence of nut 26 as is well understood. The body of the blade 28, however, is vertically guided between a pair of relatively thin leaves 29 secured to the spaced sides of the knife guard 12. It follows therefore that during rotation of shaft 16, the blade is reciprocated vertically in the relatively narrow throat or channel formed by the spaced leaves secured to knife guard 12.

In actual practice, it is desired to sharpen the blade without removing the latter from the guard. According to the invention this function may be conveniently accomplished by a pair of grinding or sharpening wheels 30 which may be shifted to straddle the blade. These wheels alternately impact opposing faces of the blade during reciprocation of the latter. Each of the sharpening wheels is rotatably mounted on the shank of a vertical rivet 31 fastened to a pair of vertically spaced extensions 32 of a fork 33 having a cylindrical spindle 34 slidably and adjustably mounted in a bushing or sleeve 35. More particularly a clamping set screw 36 is utilized to hold a spindle 34 in an adjusted and set position in respect to its associated bushing 35.

Bushings 35 may be said to constitute spaced arms straddling central block 37 with which they constitute for purposes of specification a vertically shiftable and rotatable or oscillatable yoke or carriage generally denoted 38. One arm 35 of this carriage is permanently fixed to an overhanging portion 39 of the transversely disposed shaft 40 rotatably and slidably mounted within bore 41 of block 37, that is, eye 42 of the fixed arm is permanently secured to overhanging portion 39 of shaft 40. Eye 42, however, is provided with a laterally extending finger gripping member 43, which if manipulated under certain conditions may be utilized to slide and rotate shaft 40 relative to block 37.

The other arm or bushing 35 of sharpening supporting carriage 38 is slidably mounted on the overhanging portion 44 of shaft 40. Particularly, however, eye or strap 45 of this arm may be rectilinearly and slidably displaced relative to shaft 40 although non-rotatably mounted thereon by reason of the key effect formed by the mutual contacting rectilinear faces 46 and 47 of the overhanging shaft portion 44 and eye 45 respectively.

Eye 45 of the slidable arm of the carriage is provided with a laterally projecting hollow rim 75 or finger gripping housing 48 in which the ter-

minal 49 of overhanging portion 44 of shaft 40 extends. Helicoidal spring 50 surrounds terminal 49 and has one end abutting the annular and inner shoulder 51 of the housing 48 and another end abutting an annular shoulder formed by ring 53 removably retained against the end face of terminal 49 by the threaded and adjustable set screw 54.

The normal action of spring 50 is such as to urge and set eyes 42 and 45 against companion rectilinear side faces 55 of the central block 37 provided of course locking detent 56 of eye 42 of the fixed arm 35 is locked within either of the cooperating recesses or indentations 57 and 69. In such locking relation shaft 40 is prevented from rotation about its longitudinal axis relative to block 37. In the position illustrated in Fig. 9 the fixed and movable arms 35 extend forwardly of block 37 to straddle the guard and the locking detent 57 of eye 42 is within indent 57 of block 37. Therefore shaft 40 cannot be rotated relative to block 37. In such relation, however, carriage 38 may be slidably and vertically displaced along a vertical cylindrical guide and fulcrum post 60 fixedly interposed between base 11 and the overhanging platform 13. More particularly fixed post 60 slidably guides vertical displacement of carriage 38 by reason of a cylindrical sleeve or bearing 61 closely but loosely and concentrically surrounding post 60, which sleeve 61 is fixed to and depends from central block 37 of the carriage 38.

It will be noted that sleeve 61 extends within bore 62 of block 37 and is provided with a semi-circular cut out groove portion 63 while the central part of shaft 40 is provided with a reduced portion 64 forming groove 65 which in part receives and interlocks with post 60 thereby preventing rotation of shaft 40 about its horizontal axis, that is, as illustrated in Figs. 7 and 8 shaft 40 cannot be rotated relative to its carriage 38 although sleeve 61 may be manually swiveled or partially rotated horizontally to correspondingly oscillate the carriage and thus displace the spaced grinding wheels 30 to alternately impact the sides of the blade and form the desired sharpening edge. In other words, carriage 38 may be slidably guided along post 60 and simultaneously the sharpening wheels carried by arms of the carriage may be severally moved into and out of contact with the forward vertical edge of the blade during reciprocation of the latter even though shaft 40 is locked against rotation about its longitudinal axis since in effect fulcrum post 60 in part is received by groove 65, thus forming a pivoted or swiveled connection.

With sharpening operation concluded, carriage 38 is moved to the upper part of the guard until reduced portion 64 of shaft 40 is in alignment with an attenuated portion 66 of post 60. Thus shaft 40 is disconnected from fulcrum post 60. Thereafter manipulator 43 is grasped and moved outwardly. Therefore two important functions take place. First, shaft 40 is slidably displaced relative to block 37 against the normal action of spring 51. Second, locking projection or detent 56 is moved out of indent 57. If therefore manipulator 43 is rotated, shaft 40 is rotated relative to block 37 and the reduced portion 64 of shaft 40 (see Fig. 8) enters groove 67 formed by the attenuated part 66 and interlocks with the latter.

With grinding wheels 30 in the full line position shown in Fig. 1, and shaft 40 set to be free of post 60, shaft 40 may be rotated clockwise by actuating manipulating member 43. Thus arms

of the carriage are swung downwardly and rearwardly towards the rear of the guard 12 until detent 56 is in alignment with recess or indent 69 of block 37 at which time manual pressure is released from manipulator 43 and the action of the spring 51 automatically forces shaft 40 to rotate relative to the central block whereby detent 56 enters and interlocks with indent 69 of block 37. The provided reduced part of shaft 40 is interlocked with the walls of groove 67 as shown in Fig. 8, that is, the arms of the carriage may be swung away from the sides of the guard and in back of the blade to be in an ineffective position underneath platform 13. Thus the grinding wheels are disposed rearwardly of the guard and do not straddle the sides of the latter. In this ineffective position of the grinding wheels, carriage 33 cannot be vertically displaced relative to post 60 since the reduced portion 64 of shaft 40 interlocked with the walls defined by groove 67 and seated on lower stop shoulder 68 formed by the latter.

When shaft 16 of the prime mover is rotating, blade 28 is reciprocably guided. Even during this operation, the grinding wheels may be thrown from the set and ineffective position indicated by the dash and dot lines in Fig. 1 to their full line effective position. In this connection, finger gripping member 43 is first moved outwardly to disconnect fixed arm 35 from block 37. Subsequently finger gripping member 43 is rotated to rotate shaft 40 counterclockwise. Therefore arms 35 of the carriage are moved downwardly, then upwardly, until they assume a horizontal position straddling the sides of the knife guard 2. In this position detent 56 registers with indent 57. Finger pressure is now released from manipulator 43 and detent 56 automatically enters indent 57. Hence arms 35 are locked and cannot rotate relative to the pivoted block 37.

With arms 35 straddling the knife guard and locked against rotation block 37 of the sharpening supporting means or carriage 38, however, may be reciprocably guided relatively along guide post 60, that is, block 37 is now unlocked and may be moved up and down vertically. However, in the unlocked position of block 37 the latter may also be swiveled or rotated relative to post 60, thus causing sharpening wheels 31 carried by arms 35 to alternately impact opposing faces of the blade or knife during reciprocation of the latter. During such contact the grinding wheels are rotated by the reciprocating blade and during sharpening periods the carriage is manually locked or swiveled about guide post 60 and at the same time may be moved vertically therewith.

As previously pointed out one of the chief advantages of the invention resides in the provision of sharpening means which may be quickly arranged on front of the blade to sharpen the latter and pursuant to such operation the sharpening means may be quickly shifted to be at the back of the blade and out of the way. In Fig. 8 the sharpening wheels are at the top of the guard and in back thereof. In such position the carriage is prevented from downward displacement since reduced portion 64 of the slidable and rotatable shaft 40 is confined in recesses 67. In such relation the arms of the carriage are locked with the oscillatable block 37. Even though grinding wheels are in back of the blade lateral displacement thereof is limited by lips 35' striking guard 12.

With the carriage in the position illustrated in

Fig. 8, the grinding wheels may be quickly shifted or swung to the front of the blade. In this connection, manipulator 43 is grasped and moved outwardly. Consequently detent 56 is removed from indent 69 and shaft 40 is slidably moved transversely relative block 37. Hence spring 51 is compressed. Since shaft 40 is now free to rotate, the knurled head 43 is rotatably manipulated, thus swinging arms 35 to dispose the grinding wheels in the front of the blade until indent 56 is in alignment with indent 57 at which time the manipulator 43 is released and as a result of the expansion of spring 51 shaft 40 is caused to slide inwardly relative to block or member 37. Consequently groove 65 is now side by side groove 57 of the attenuated portion 66. Therefore the carriage is released from lower shoulder 68 and now may be slidably moved along post 60. At this time, also indent 57 receives detent 56. Therefore arms 35 are prevented from rotation relative to the slidable and rotatable block 37.

It will be noted that the opposite parts of the reduced portion 64 of shaft 40 has several functions. When the grinding wheels are at the front of the blade groove 65 in part receives post 60 (Fig. 25 9) and hence a pivotal connection is formed with fulcrum post 60. With the arms 35 at the rear of the guard reduced portion 64 is confined within groove 67, thus cooperating to prevent vertical displacement of the carriage. With the present 30 construction it will be apparent that if the grinding wheels are at the front of the blade, they can be shifted to the rear of the guard provided the carriage is first moved upwardly to the top of the guard so that grooves 65 and 67 are in communication at which time shaft 40 may be rotated provided detent 56 is out of indent 57.

In actual practice, one of the grinding wheels may wear at a faster rate than the other. Consequently the character of the knife edge obtained 40 during the process of sharpening is varied. With the present invention means has been provided to control the relation of the grinding wheels in respect to the blade to obtain a substantially uniform type of edge even though the grinding wheels 45 may wear at different rates. In this connection the upper extension 32 of each of the forks 33 is provided with a pointed index or tapered projection 71. These projections are set to be disposed in alignment with the feathered edge 50 of the blade by means of an index line 72 ground into the upper surface of each wheel. Hence the grinding or sharpening wheels strike the beveled faces 73 of the blade at the proper angle to form the desired cutting edge. In case where one of 55 the grinding wheels does not properly strike the adjacent beveled face of the blade, its spindle 34 may be slidably adjusted relative to its arm 35 and subsequently clamped in the set position by set screw 36.

According to the invention the blade is provided with a sinuous or irregular edge 75. The edge is maintained during the course of sharpening by reducing the body of the blade. In this connection, it will be observed that in effect the 60 blade comprises a plurality of spaced teeth 76 forming grooves 77 each in horizontal alignment with opposed recesses 78 to characterize a reduced or attenuated portion 79 in the body of the blade. By reason of such construction the reduced portions of the blade are slightly weaker than the body of the latter and consequently wear more readily during sharpening operations and thus the toothed effect of the irregular or tortuous cutting edge is maintained during the process 75

of sharpening and during such operations vertical movement of the carriage 38 is limited by lug 80 projecting from guard 12 during the upward stroke of the carriage and by the depending guide sleeve 61 abutting base 11 on the downward stroke of the carriage.

A stack of cloth 81 is placed on the forward part of base 11 and a forked presser foot 82 holds the cloth in a set position. The presser foot is carried by a square rod 83 slidably guided in grooved and spaced shoes or tracks 84 secured to the offset plate 85 having its side wall 86 fixedly fastened to lug 14 depending from the casing of motor 15. A brake latch 87 has a square guide hole 87' at one of its ends for receiving the square rod 83 and has another end loosely disposed between a pair of posts 88 projecting rearwardly of the front cover plate 89.

Latch 87 is actuated by pivoted lever 90. Specifically, however, lever 90 is pivoted to closure plate 89 by set screw 91 and is provided with an offset lug 92 disposed in gap 93 (Fig. 5) formed by the bifurcated portion 94 of the manipulatable lever 95 (Fig. 1) which has an intermediate portion thereof pivoted on the set screw 96 adjustably fastened to lip 97 of closure plate 89 which in turn is secured to shoes 84 by set screws 84'.

When the manipulating portion 98 of lever 95 is moved in a direction towards depending lug 14 of the motor casing its bifurcated end 94 is moved outwardly, hence lever 90 is actuated and pivots on set screw 91. Therefore bifurcated portion 99 which straddles the braking latch 87 is released and moves downwardly, that is, the sides 35 of the squared opening become frictionally free of rod 83 and consequently the latter drops by gravity such that its presser foot rests upon the uppermost layer of the stack of cloth.

If finger pressure be removed from manipulating portion 98, resilient wired spring 100 automatically urges the latter outwardly, thereby tilting lever 90 in an opposite direction to assume an inclined position as shown in Fig. 5 whereby the inclined walls of the square hole 87' abut the 45 sides of the square rod 83 and the latter is braked or held in a set position. Spring 100 has one end 101 fastened to lever 95, an intermediate portion 102 coiled about shank of set screw 96 and an offset end 103 fastened to the closure plate 89. With this arrangement, manipulating portion 98 is normally urged outwardly and consequently the brake latch is normally braced against rod 83 to hold the latter in a set position.

In the form according to Figs. 11 and 12, the 55 oscillatable carriage 38 comprises diverging arms 110 and 111 each of which is provided with an eye 112 interposed between annular flanges 113, 114 and 115. Flanges 113 and 114 are fixedly secured to the vertically disposed bearing 116 having groove 117 the curved wall of which cooperates with the curved end 118 of guard 12 to define a removable swivel or pivotal connection permitting diverging arms 110 of the carriage to be horizontally swung towards and from the blade.

60 Annular flange 115 is a part of sleeve 119 and the hollow concentric nipple 120 projects upwardly from flange 115. Encircling nipple 120 are the spaced eyes 112 of the diverging arms 110 and also encircling nipple 120 are the annular flanges 113 and 114 carried by the semi-circularly grooved shaped bearing 116 of the carriage. The bores of flanges 113, 114 and 115 as well as bore of eyes 112 are in vertical alinement as shown to permit insertion, if desired of a guide post 60 of 75 the type shown in Fig. 1 where it is desired to

guide the sharpening supporting means in the manner shown in Fig. 1. In Figs. 11 and 12, the sharpening supporting means may be considered as a unit which may be conveniently applied to the guard 12 and quickly removed therefrom. applied to the guard 12, it may be slidably and vertically displaced relative to guard 12 and the same time oscillated by holding bearing 1 against curved end 118 of the knife guard in motion to and fro transversely of the guard whereby the grinding and sharpening wheels alternately impact the blade during its reciprocation. In Figs. 11 and 12 each arm 110 carries an adjustable clamping member 121 on which a fork 33 is slidably mounted. Each fork in Figs. 11 and 12 is provided with a rearwardly disposed slotted extension 121' slidably mounted on the shank of clamping member 121 and rotatably carries the horizontally disposed grinding wheel for cooperating with the reciprocating blade to sharpen the edge of the latter.

In the form according to Figs. 13 and 14, carriage 38 of the sharpening supporting means of the type disclosed in connection with Figs. 1-10 but the central block 37 thereof is vertically and slidably guided on a square post 11 having its ends 126 rotatably journalled in bearings 127 and 128 of the platform 13 and base 1. One end 126 of post 125 is fixedly connected to an arm 129 which has an upstanding projection 130 having opening 131 confining one end of arm 132 having its eye shaped end 133 pivotally sustained by shank of set screw 134. Arm 132 is surrounded by spring 135 which acts to hold arm 129 in a set position. In operation, finger gripping members 43 and 48 are grasped and shifted to and fro horizontally. Hence squared post 11 is oscillated which in turn oscillates carriage 38. Consequently the grinding wheels straddling the blade alternately impact opposing faces thereof. During such operation, however, carriage 38 may be slidably and vertically moved along the guide post 125. In other aspects, the form illustrated in Figs. 13 and 14 is along the lines of Figs. 1 to 8 inclusive.

According to the form shown in Figs. 15 and 16 the sharpening supporting means may be conveniently applied to or disconnected from the knife guard 12 and from the base of the machine. In this connection the sharpening supporting means 38 is rotatably and slidably mounted on post 140 attached to base plate 11 removably placed on base 11. Carriage 38 includes a depending knurled sleeve 142 which surrounds post 140 and is slidable relative thereto for vertically displacing the grinding wheel. During displacement of sleeve 142, the latter also rotated in one direction and subsequently in the opposite direction, thus causing the grinding wheels to alternately impact opposing faces of the blade.

The sharpening supporting assembly unit of Figs. 15 and 16 although disconnectably associated with guard 12 may in fact be removably clamped thereto. For this purpose a pair of pivotally interconnected jaws 150 and 151 is provided. These jaws are pivotally mounted on fulcrum pin 152 attached to base plate 141. Lip 153 of these jaws embrace guard 12 and are clamped thereto by adjusting set screw 154 which if rotated in one direction causes ends 155 to separate to bring lips 153 towards each other and by which if rotated in an opposite direction lips 153 are caused to diverge and be free of the guard and thus permitting base plate 141 together

with its sharpening supporting carriage to be bodily removed from base 11 by the aid of handle 156. In such event the entire sharpening assembly support is quickly removed from the base of the machine and the blade is free of the grinding wheels.

According to Figs. 17 and 18, a circular blade is illustrated. This type of blade is employed in connection with the so called rotary cloth cutting machine well known in the art. The blade illustrated in Fig. 17, however, differs from those heretofore utilized in connection with the rotary cutting machines in that its cutting edge is sinuous or irregular in contour to provide a plurality of circumferentially disposed and spaced teeth. This effect is maintained even during sharpening periods since the blade is provided with a plurality of spaced attenuated portions 160. In this instance, the attenuated portions are radially arranged and as in the case of the form shown in Fig. 2, are relatively weaker than the body of the blade and consequently wear more readily during grinding.

The blade illustrated in Figs. 2 and 17 present an edge having spaced teeth which in operation simulate the action of a saw. In passing through a stack of cloth this type of edge produces a relatively clean sharp cut without tearing any of the layers of the stack, and in actual practice, this type of edge has been found to stand up for appreciable long operating periods even though subjected to relatively heavy duty.

With the grinding wheels 30 in position for sharpening as shown in Fig. 9, carriage 38 may be bodily rotated or oscillated to permit wheels 39 to impact the opposing sides of the edge of the blade. During each cycle each wheel contacts the blade due to the manual pressure applied to the carriage. Although each wheel is held momentarily against the reciprocating blade, in actual practice, it has been discovered that undulating edge of the blade because of the irregular or interrupted contour has a tendency to vibrate the impacting grinding wheel even against the resistance of the manual pressure applied to the carriage and even though the impacting wheel is against the reciprocating blade. This principle it has been discovered not only has a tendency to increase the sharpness of the edge of the blade but it has been also found that the spaced attenuated portions 78 of the blade will wear more rapidly than the teeth 76 thereon and notwithstanding the fact the latter are sharpened, the undulating form of the cutting edge is maintained.

Without further analysis, the foregoing disclosure will so fully reveal the gist of the present invention that others can by applying current knowledge readily adapt it to various applications without omitting certain features, that from the standpoint of the prior art, fairly constitute the essential characteristics of the generic and specific aspects of the invention and therefore such adaptations should and are intended to be comprehended within the meaning and range of equivalency of the following claims.

I claim:

1. In combination, a guard for slidably holding a blade, means for reciprocating said blade, a carriage, means slidably guiding said carriage, pivotal means for oscillating said carriage, sharpening means sustained by said carriage and adapted to be disposed at the front of said blade, means for shifting said sharpening means to be disposed at the rear of said blade, locking means

to prevent displacement of said sharpening means to the rear of said blade when disposed at the front of said blade, locking means to prevent displacement of said sharpening means to the front of said blade when disposed at the rear of said blade, and means to prevent vertical displacement of said carriage when said sharpening means is disposed at the rear of said blade.

2. In combination with a movably guided blade, of a vertically guided carriage pivotally and transversely displaceable relative to said blade, sharpening means straddling said blade and carried by said carriage, means for swinging said sharpening means to dispose the latter from the rear to the front of said blade to permit the latter to be alternately impacted by said sharpening means during oscillation of said carriage, means for slidably guiding said carriage when said sharpening means is disposed at the front of said blade, and locking means to prevent shifting of said sharpening means to the rear of said blade when the latter is disposed at the front of said blade.

3. In combination, a guard for movably guiding a blade, means for reciprocating said blade, a guide disposed rearwardly of said guard, a carriage having an intermediate portion slidably guided by said guide, a rotatable member carried by said portion, spaced arms mounted on said member, means carried by each of said arms for supporting a grinding wheel, locking means to prevent rotation of said arms and member relative to said intermediate portion, and a pivotal connection between said guide and member to permit swinging of said carriage in respect to said guard for alternately disposing said grinding wheels in contact with said blade during reciprocation thereof.

4. In combination, a guard for movably guiding a blade, means for reciprocating said blade, a guide disposed rearwardly of said guard, a carriage having an intermediate portion slidably guided by said guard, a rotatable shaft carried by said portion, an arm fixed to said shaft, a grinding wheel carried by said arm, an arm slidably and non-rotatably connected to said shaft, a grinding wheel carried by said slidably arm, and locking means to prevent rotation of said shaft and arms relative to said member during vertical displacement of said carriage relative to said guard, said grinding wheels straddling the forward portion of said blade during vertical reciprocation of said carriage, said guide having means to permit transverse displacement of said shaft relative to said carriage for releasing said locking means, said shaft upon releasing of said locking means being rotatable relative to said intermediate portion for moving said arms and grinding wheels to the rear of said guard.

5. In combination, a guard for movably guiding a blade, means for reciprocating said blade, a guide disposed rearwardly of said guard, a member slidably mounted on said guide, a shaft slidably and rotatably carried by said member, an arm secured to said shaft, a grinding wheel carried by said arm, an arm slidably and non-rotatably mounted on said shaft, and a grinding wheel carried by said slidably arm, said shaft and guide having means constituting a pivotal connection to prevent sliding and rotation of said shaft relative to said member and permitting transverse displacement of said arms relative to said member, said shaft and guide having coop-

erating means to prevent displacement of said member relative to said guide.

6. In combination, a guard for movably guiding a blade, means for reciprocating said blade, a guide disposed rearwardly of said guard, a member slidably mounted on said guide, a shaft slidably and rotatably carried by said member, an arm secured to said shaft, a grinding wheel carried by said arm, an arm slidably and non-rotatably mounted on said shaft, and a grinding wheel carried by said slidable arm, said shaft and guide having means constituting a pivotal connection to permit vertical displacement of said member and arms relative to said guide and to prevent rotational and lateral displacement of said shaft relative to said member for displacing said arms transversely of said member to alternately dispose said wheels in and out of contact with said blade.
7. In combination, a guard for movably guiding a blade, means for reciprocating said blade, a guide disposed rearwardly of said guard, a member slidably mounted on said guide, a shaft slidably and rotatably carried by said member, an arm secured to said shaft, a grinding wheel carried by said arm, an arm slidably and non-rotatably mounted on said shaft, a grinding wheel carried by said slidable arm, said shaft and guide having means constituting a pivotal connection to prevent displacement of said shaft relative to said member and permitting displacement of said arms to alternately dispose said wheels when disposed forwardly of said guard in and out of contact with said blade, locking means to prevent rotation of said arms relative to said member when said wheels are disposed forwardly of said blade, said shaft and guide having means to permit rotation of said shaft upon release of said locking means to permit rotation of said shaft relative to said member for positioning said arms rearwardly of said guard, and locking means to prevent rotation of said arms

relative to said member when said arms are positioned at the rear of said guard.

8. In combination, a guard for movably guiding a blade, means for reciprocating said blade, a guide disposed rearwardly of said guard, a vertically displaceable member slidably mounted on said guide, a shaft slidably and rotatably carried by said member, an arm secured to said shaft, a rotatable grinding wheel carried by said arm, an arm slidably and non-rotatably mounted on said shaft, a grinding wheel rotatably carried by said slidable arm, said shaft and guide having means constituting a pivotal connection to prevent lateral and rotational displacement of said shaft relative to said member and permitting transverse displacement of said arms relative to said member to alternately dispose said wheels when disposed forwardly of said guard in and out of contact with said blade, locking means to prevent rotation of said arms relative to said member when said wheels are disposed forwardly of said blade, said guide having means to permit rotation of said shaft relative to said member upon release of said locking means for positioning said arms rearwardly of said guard, and locking means to prevent rotation of said shaft when said arms are positioned at the rear of said guard, said shaft and guide having means to prevent downward displacement of said member when said arms are positioned to the rear of said guard.

9. In combination, a base having an upstanding guard, a removable support mounted on said base and having an upstanding guide, pivoted means slidably mounted on said guide comprising arms removably straddling said guard, grinding wheels carried by said arms and adapted to impact opposing faces of said blade during oscillation of said pivoted means, and clamping means associated with said support for removably embracing said guard.

SAMUEL SEGAL.
